UNITED STATES PATENT OFFICE.

EINAR MORTERUD, OF TORDERÓD, NEAR MOSS, NORWAY.

APPARATUS FOR TRANSMITTING HEAT FROM ONE MEDIUM TO ANOTHER.

No. 900,411.

Specification of Letters Patent. Patented Oct. 6, 1908.

Application filed March 11, 1908. Serial No. 420,462.

To all whom it may concern:

Be it known that I, EINAR MORTERUD, a subject of the King of Norway, residing at Torderód, near Moss, in the Kingdom of Norway, have invented certain new and useful Improvements in Apparatus for Transmitting Heat from one Medium to Another; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to apparatus for transmitting heat from one medium to another, as for instance, steam-boilers, condensers, feed water heaters, heaters used with cellulose digesters and the like.

My invention relates more especially to that class of heaters in which freely expanding tubes constitute the body through which the heat is transmitted.

Examples of such apparatus are shown in the accompanying drawing, in which—

Figure 1 is a longitudinal section through a heater particularly adapted for use in cellulose factories; Fig. 2 is a cross section of the same, and Fig. 3 is a longitudinal section of a steam boiler.

In Figs. 1 and 2 the heater is composed of three castings, A, B and C, suitably bolted together, and a plurality of U-shaped tubes E secured in a plate D held between the castings A and B. The casting A has a partition F. The fluid to be heated passes in at G, enters the bent tubes and passes out at H. The heating medium passes in at I in the casting B, rises within the latter and passes out at K.

In a heating apparatus of this and similar kinds the coefficient of heat transmission is dependent on the velocity with which the heating medium circulates; the greater the velocity the greater the coefficient of transmission. Great velocity of the heating media is also advantageous for other reasons, as for instance, to prevent or diminish the formation of deposits of soot, boiler scale and the like on the surfaces of the heating

bodies or tubes. It is therefore advantageous to reduce the areas through which the heating medium passes, and my invention consists, in forming the tubes so that the space left for the passage of the heating medium is as small as possible. I attain this by using tubes, the portion of which nearest the tube-plate is of considerably smaller diameter than the free end of the tubes, constituting the larger part of the heating surface. In this manner the area around the tubes in the upper part may be considerably reduced and at the same time the tubes will not, at the lower end of the heater, obstruct the entrance of the heating medium in a lateral direction between the tubes.

The steam boiler shown in Fig. 3 comprises a steam drum a, water box b having a partition c, and field tubes d with inner circulating tubes e fitted into the partition plate c. The tubes are provided with a narrower part nearest the water box, so that sufficient free space is left between the tubes for the passage of the fire gases in a lateral direction. Where the gases pass in an axial direction between the tubes the space will be narrow and a great velocity of the heating gases secured. In a similar way, by letting the inner tubes have a larger diameter, where the field tubes have a large diameter, the water space between the tubes will be kept narrow all the way and secure a rapid flow of the water.

I claim—

An apparatus for transmitting heat from one medium to another, comprising a tube plate, a casing adapted to serve as a conduit for a heat transmitting medium having a lateral opening near the tube plate, and freely expanding tubes in the said tube plate, said tubes being reduced in diameter at the part extending from the tube plate past said opening.

In testimony that I claim the foregoing as my invention, I have signed my name in presence of two subscribing witnesses.

EINAR MORTERUD.
